DE WITT C. HAMILTON

MANUFACTURE OF GLASSWARE

Filed July 16, 1924.

UNITED STATES PATENT OFFICE.

DE WITT C. HAMILTON, OF SAPULPA, OKLAHOMA, ASSIGNOR TO THE BARTLETT-COLLINS GLASS COMPANY, OF SAPULPA, OKLAHOMA, A CORPORATION OF OKLAHOMA.

MANUFACTURE OF GLASSWARE.

Application filed July 16, 1924. Serial No. 726,307.

To all whom it may concern:

Be it known that I, DE WITT C. HAMILTON, a citizen of the United States, residing at Sapulpa, county of Creek, and State of Oklahoma, have invented a new and useful Improvement in the Manufacture of Glassware, of which the following is a full, clear, and exact description.

The present invention relates to the manufacture of glassware, and more particularly to a method of making stemmed articles, such as goblets.

An object of the invention is to provide a method whereby the bowl and stem of a blown article can be formed integrally in one operation from a pressed blank. Another object of the invention is to provide such a method that enables an increased production, greatly reduces labor costs and eliminates all seams in the articles produced.

In the accompanying drawings:

Figure 1 is a sectional view of a forming or pressing mold, a formed or pressed blank being shown in the mold;

Figure 2 is a sectional view of a blowing mold, showing the previously formed or pressed blank in section and the blown article in elevation; and

Figure 3 is an elevation of a completed article.

In carrying out my improved method, I first place a charge of molten glass in the cavity 2 of a forming or pressing mold 3. This is preferably a block mold made in one piece, with an ejector 4 positioned in a recess 5 in its lower end, the ejector having a stem 6 fitting in the lower end of the cavity. The upper end of the mold cavity is countersunk as indicated at 7, and is formed with a recess 8 to receive a cover 9 having a central bore 10 countersunk at its lower end at 11 to match the countersink 7. A plunger 12 is adapted to be inserted into the charge in the mold cavity through the bore 10, after the cover is in position to compact the charge and form the hollow bowl portion of the blank. When the plunger is inserted in this manner, the glass is forced into the annular recess constituted by the countersinks 7 and 11, and a bead 13 is formed at the upper end of the blank.

After the blank has been formed or pressed in the manner illustrated in Figure 1 with an integral stem 8 as shown, the plunger 12 is withdrawn and the cover 9 removed. The

blank is then ejected by means of the ejector 4 and transferred to the blowing mold 14, shown in Figure 2. This mold is also preferably made in one piece with an enlarged cavity 15 of a size corresponding to that of the bowl portion of the article to be produced from the blank. The lower end portion 16 of the cavity is of the same size as the corresponding end of the cavity 2 of the forming or pressing mold, so that the stem 6 of the portion of the blank just fits therein.

The mold 14 is provided with a sectional cover 17, the two parts of which are hinged to swing on a vertical pin 18 carried by a lateral projection 19 integral with the upper end portion of the blow mold. The sections of the cover are formed with a rib 20 adapted to have interlocking engagement with a rib 21 at the upper end of the mold when the two parts of the cover are brought together. It will be understood that the cover is provided with suitable means for locking the parts thereof in closed position. The cover 17 is provided with a cavity 22, the lower end of which is of the same diameter as that of the upper end of the cavity 15. The cavity 22 gradually decreases in diameter from bottom to top and is countersunk at its upper end as indicated at 23, thereby providing an inwardly extending annular rib 24.

When the formed or pressed blank is positioned in the blowing mold, the bead 13 at its upper end seats on the rib 24, while the integral stem 8 fills the cavity 16. The lower end of the stem rests on a block 25 fitting a recess 26 in the lower end of the mold. When the blank is in the position shown, blowing fluid, as for example compressed air, is introduced into the cavity 27 of the blank and the bowl portion of the blank, expanded into conforming relation with the walls of the cavities 15 and 22 in the mold and its cover, thereby forming the bowl portion of the blank to the size and shape desired. After this step, the cover 17 is opened and the blown blank removed. The top portion of the blank having the bead 13 is then cracked off along the line 28, and a base or foot 29 is cast on the lower end of the stem in the usual manner, thus producing the finished article illustrated in Figure 3.

The advantages of my invention are that it provides a method whereby the bowl part and the stem of a blown article can be

formed integrally from a pressed blank in one operation, and with a one-piece mold, thereby eliminating all seams such as found on articles produced in jointed molds. Moreover, machines can be used in carrying out the steps of the method to increase the production and greatly reduce labor costs.

While I have described a preferred manner of carrying out my method and have shown suitable apparatus which may be used in carrying out the steps thereof, it will be understood that the invention is not limited to the details disclosed, but may be varied within the scope of the appended claims.

15 I claim:

1. The method of making a stemmed article of glassware, comprising placing a charge of molten glass in the cavity of a blank forming mold, inserting a plunger 20 into said cavity to form the bowl portion of the blank having an integral stem depending therefrom, withdrawing the plunger, removing the blank from the forming mold and placing it in a one-piece blowing mold, and blowing the bowl portion of the blank into the desired form, substantially as described.

2. The method of making a stemmed article of glassware, comprising placing a charge of molten glass in the cavity of a

one-piece mold, inserting a plunger into said cavity to form the bowl portion of the blank having an integral stem depending therefrom, withdrawing the plunger, removing the blank from the forming mold and placing it in a one-piece blowing mold, and blowing the bowl portion of the blank into the desired form, substantially as described.

3. The method of making a stemmed article of glassware, comprising forming a blank with a stem portion and a hollow bowl portion, placing said blank in a one-piece blowing mold, and blowing the bowl portion of said blank to the desired form, substantially as described.

4. The method of making a stemmed article of glassware, comprising pressing a blank with a stem portion and a hollow bowl portion in a one-piece mold, removing the pressed blank from said mold and placing it in a one-piece blowing mold, blowing the bowl portion of said blank to the desired form, and casting a base or foot onto the lower end of said stem, substantially as described.

In testimony whereof I have hereunto set 55 my hand.

DE WITT C. HAMILTON.
